US00D996212S

(12) **United States Design Patent** (10) Patent No.: **US D996,212 S**
(45) Date of Patent: **** Aug. 22, 2023**

(54) **LID FOR PACKAGING**

(71) Applicant: **TETRA LAVAL HOLDINGS & FINANCE S.A.**, Pully (CH)

(72) Inventors: **Paolo Zanon**, Modena (IT); **Anna Rosa Vietri**, Modena (IT); **Pietro Martini**, Parma (IT); **Marco Insero**, Bologna (IT)

(73) Assignee: **TETRA LAVAL HOLDINGS & FINANCE S.A.**, Pully (CH)

(**) Term: **15 Years**

(21) Appl. No.: **35/512,506**

(22) Filed: **Mar. 5, 2021**

(80) **Hague Agreement Data**

Int. Filing Date: **Mar. 5, 2021**

Int. Reg. No.: **DM/213979**

Int. Reg. Date: **Mar. 5, 2021**

Int. Reg. Pub. Date: **Sep. 10, 2021**

(30) **Foreign Application Priority Data**

Sep. 7, 2020 (EM) 008159792

(57) **CLAIM**

The ornamental design for a lid for packaging, as shown and described.

DESCRIPTION

1. Lid for packaging
2. Lid for packaging
- 1.1: Perspective
- 1.2: Right side view
- 1.3: Left side view
- 1.4: Back side view
- 1.5: Front side view
- 1.6: Top side view
- 1.7: Bottom side view
- 2.1: Perspective
- 2.2: Right side view
- 2.3: Left side view
- 2.4: Back side view
- 2.5: Front side view
- 2.6: Top side view
- 2.7: Bottom side view

The broken lines are shown for the purpose of illustrating parts of the article that form no part of the claimed design.

1 Claim, 14 Drawing Sheets
